UNITED STATES PATENT OFFICE.

WESLY F. JUREY, OF NORCATUR, KANSAS.

MASK FOR ANIMALS.

Application filed September 10, 1924. Serial No. 736,966.

To all whom it may concern:

Be it known that I, WESLY F. JUREY, a citizen of the United States, residing at Norcatur, in the county of Decatur and State of Kansas, have invented new and useful Improvements in Masks for Animals, of which the following is a specification.

This invention relates to devices for use upon animals and has for its object the provision of a novel mask or shield designed to be engaged upon the heads of stock to cover the eyes, the portions which extend over the eyes being formed with openings adapted to be closed to a greater or less extent by means of shutters.

An important object is the provision of a device of this character which is adjustable for use upon animals having different sized heads.

20 An additional object is the provision of a device of this character which will be simple and inexpensive in manufacture, easy to apply and adjust, positive in action, efficient and durable in service and a general improvement in the art.

With the above and other objects and advantages in view the invention consists in the details of construction to be hereinafter more fully described and claimed and illustrated in the accompanying drawings, in which:

Figure 1 is a perspective view of the device showing it mounted in place on the head of an animal,

35 Figure 2 is a rear elevation with the straps removed showing the adjustment feature,

Figure 3 is a cross section on a larger scale taken on the line 3—3 of Figure 1,

40 Figure 4 is a central longitudinal section, Figure 5 is a longitudinal section taken through one of the shutters,

Figure 6 is a detail perspective view of a shutter alone.

Referring more particularly to the drawings I have shown my device as comprising a pair of plates 10 and 11 which are curved in cross section and which are shaped in general to fit conformingly upon the head of an animal. The plate 10 is of greater width than the plate 11 so that when both plates are arranged to have the general shape of a trapezoid when viewed from the front the plates will be in overlapping relation at their upper inner corners. Furthermore at its 55 upper inner corner the plate 10 is formed

with a guide flange 12 within which the plate 11 is slidable and which operates to prevent upward displacement of the plates with respect to each other. The plates are pivotally connected at their lower inner corners as shown at 13 and may be held at any desired adjusted position by means of a clamping bolt 14 which passes through the plate 11 and also through an elongated slot 15 in the plate 10.

Each plate is formed with a series of elongated slots 16 at a point which will come over the eyes of the animal when the device is applied. At opposite sides of the series of slots are guides 17 within which is slidably mounted a shutter plate 18 adapted to be brought more or less in registration with the slots 16 for closing them to the desired extent. At their upper ends the shutters are outturned as indicated at 19 to define finger grips which will facilitate adjustment.

For holding the device upon the animal's head, I provide a neck encircling strap 20 equipped with a buckle 21, and connected with this strap are spaced brow straps 22 which extend up over the top of the animal's head, while connected with the lower outer corners of the plates are cheek straps 23 which are connected with the main strap 20.

The device is of course adjusted to fit the individual animal to which it is applied and it is obvious that in use the shutters may be entirely or almost entirely closed so as to protect the animal's eyes. It is believed from the foregoing that the construction, operation and advantages may be readily apparent without further elaboration.

While I have shown and described the preferred embodiment of my invention it is of course to be understood that I reserve the right to make such changes in the form, construction and arrangement of parts as will not depart from the spirit of the invention or the scope of the subjoined claims.

Having thus described my invention I claim:

1. A mask of the character described comprising a pair of adjustably connected plates curved for substantially conforming engagement upon the head of an animal to extend over the eyes, said plates being provided with slots, and means for regulating the opening of the slots, means for securing the device upon the animal's head.

2. A device of the character described comprising a shield of curved shape engageable upon the head of an animal over the eyes, adjustable strap means for mounting the device upon the head, said shield being formed with two series of slots located over the eyes, and slidably mounted shutters for regulating the size of the slots.
3. A device of the character described comprising an adjustable shield of curved shape engageable upon the head of an animal over the eyes, adjustable strap means for mounting the device upon the head, said shield being formed with two series of slots located over the eyes, and means for regulating the size of the slots, comprising slotted shutters slidably mounted and adapted to be registered with the slots to a desired extent.
4. A device of the character described comprising a shield of curved shape engageable upon the head of an animal over the eyes, adjustable strap means for mounting the device upon the head, said shield being formed with two series of slots located over the eyes, means for regulating the size of the slots, said shield being formed as two plates pivotally connected at their lower inner corners and slidably engaged at their upper inner corners whereby to be adjust-
- able for engagement upon heads of different sizes.
5. A device of the character described comprising a pair of curved plates adapted to be engaged upon the head of an animal over the eyes, securing means connected with the plates for holding the device upon the animal's head, said plates being formed over the eyes with two series of slots, guides located at opposite sides of each series of slots, and a slotted shutter slidable within each pair of guides for closing said first named slots to a desired extent.
6. An animal mask comprising a member adapted for engagement upon an animal's head to extend over the eyes and formed with openings at points opposite the eyes, and longitudinally slidable means for regulating the size of the openings.
7. In an animal mask comprising a pair of plate members adjustably connected whereby the width of the combined plate members may be varied, said plate members being shaped for substantially conformingly engagement upon the forepart of the head of an animal, the plate members having variable side openings therein at points opposite the animal's eyes.

In testimony whereof I affix my signature.
WESLY F. JUREY.
